John Bruce and Charles Bruce.

Letters Patent.

The schedule referred to in these Letters Patent and making part of the same, containing a description in the words of the said John Bruce and Charles Bruce of their improvements in the machine for manufacturing short biscuit pilot bread crackers &c.

Know all whence it may concern of these presents, that we John Burns
of the County of Kings and Charles House of the same County & State of
New York, have invented and discovered a new and useful machine for
Manufacturing or forming from the dough of flour and other usual mate-
rials, what is commonly called ship biscuit, stavy and pilot bread, and
two year cakes, ginger nuts, tea biscuits &c &c, and that a specification
of the aforesaid machine is contained in the words following. It is a
rectangular slab of suitable length, width and thickness and made of
wood or other material or materials is to be provided having its two
longest surfaces perfectly plane or level & parallel with each other. A
piece of framework is to be prepared among other things to receive this
in such a manner that its two larger surfaces may be parallel with the
horizon or as near thereto as may be convenient and in such manner
also that with the aid of a groover or grooves or other similar contrivance
made in or attached to the said frame it may be moved backward and
forward in the direction of its length a sufficient and convenient distance.
The use of this slab is to receive at one end of it and on the uppermost surface
of the same, the dough from which is intended to be made the aforesaid
ship biscuit, stavy and pilot bread, crackers, two year cakes, ginger nuts,
tea biscuits &c &c and being put in motion by any convenient power that
will serve to convey the said dough underneath two, three or more cylindrical
rollers placed one piece over the said slab, with their axes parallel to
one another and parallel also to the said slab but one being longer

Mar 13, 1832

nearer to the said slab as they are located farther from that end of the frame first receiving the dough. — The dough being thus conveyed on the said slab, underneath the said rollers is pressed into a flat form and spread evenly over and upon its surface every time it passes under any one of the said rollers becoming thinner than it was before till having passed under that roller which is farthest from that end of the frame which first receives the dough it is brought to a thickness to be to the intended thickness of the aforesaid stiff biscuit, mazyam, pilot, bread, crackers, New year cakes, ginger nuts, tea biscuits &c &c.

• & still further use of this slab, is after having in conjunction with the rollers already mentioned, pressed or spread the dough into its flat and proper form and thickness, to convey it under the cylinders hereafter and herein to be described and named the cutting cylinders for the purpose of being cut into pieces of the required shape and such as we have already mentioned. Effectually to make the said rectangular slab serve the purpose required of it, it is necessary that, to one or both vertical sides of the said slab should be attached to what is usually called a rack with teeth on its upper side working into teeth of a wheel fastened and belonging (in preference) to that particular cylindrical roller, which is next to that end of said frame, which first receives the dough, and in order to keep the dough from spreading sideways so as to run over upon itself the teeth of this said rack as also the teeth of the wheel into which it works a strip of any suitable material, and of sufficient height, is to be made fast in the uppermost surface of the said slab in such a manner as to be in the direction of its length at or near each edge of the said slab, and extending the whole or nearly the whole length thereof; Motion backwards and forwards will be alternately given to the aforesaid slab, by the use of a crank or other machine attached to the shaft of the cylindrical roller last mentioned and moved by the hand or other similarly regulated power in an alternate manner. The cylindrical rollers two, three, four, or more, of them necessary in the frame which receives and contains the aforesaid slab, they are placed over it in such manner that their axes are at right angles to the length of the slab, and by screws or any other convenient machinery they are made capable of being elevated or depressed in a steady

frame

Mar. 13, 1832

further from or approach nearer to the upper surface of the said slab, as occasion may require. A wheel (and it has been already referred to) is attached to the shaft of that particular cylindrical roller, which is nearest to that end of the aforesaid frame at which the dough is first received and works into the teeth of the rack immediately below it, giving motion to it, and of course to the slab itself to which it is permanently secured in a backward and forward manner. But if the wheel first described be made fast to the shaft of the particular cylindrical roller, above named the shaft of no other cylindrical roller can have any wheel attached to it, all other rollers will be removed by the mere contact and pressure of the dough between them and the slab. It will be understood also that the two strips intended to prevent the dough from encroaching upon the end or racks above mentioned will require that all the cylindrical rollers be so shaped as to admit the said strips to pass freely under them. They will or rather should be so shaped accordingly. The piece of machinery intended to be made use of in cutting the dough into the desired forms after it shall have been rendered flat and of an equal and proper thickness is a cylinder which we shall name the cutting cylinder supplied with what we shall call cutters. Like the cylindrical rollers already mentioned for flattening the dough it stands over or above the aforesaid slab, but in such manner as to press merely on it, and having its axis ~~across~~wise, or at right angles to the direction of the length of the slab; it is situated, in the frame further from that end of it at which the dough is first received than any of the cylindrical rollers above mentioned, and of course as near as may be to the one which brings the said dough to the desired thickness. The cutters if not made of a piece with the cylinder itself, as they may be, tho' not perhaps with the same convenience as in another manner, are inserted into the said cylinder by the aid of screw work, or otherwise, if the two unit to be of a circular shape circular holes of a suitable diameter may be drilled or bored at right angles to the axis, into the cutting cylinder, so as to penetrate into its interior the said cutting cylinder of course being hollow and either with or without the ends of the same being closed at the places of the said holes, but then
hinged

6903X

Mar 13, 1832

holes or perforations are secured or otherwise made of all short cylindrical tubes having an internal diameter equal to that which the biscuit to be, is intended to pass through. That extremity of each cylindrical tube which may be called the bottom, and which is nearest in point of distance to the axis of the aforesaid cutting cylinder has its opposite closed up with a plate either separately attached or of a piece with the tube itself. The length of each of these short cylindrical tubes should not be less than three, four, or six times the thickness of the proposed liquidation. Into every such plate when the biscuit to be required to be ~~joined~~ ^{joined} thereto be inserted and made fast thereto as many cylindrical or other shaped wires as may be necessary to perforate the biscuit to be sufficiently. These wires should be made somewhat sharp and pointed. They should be placed as near as may be equidistant from each other, and their external extremities should terminate in the external curvature of the aforesaid cutting cylinder. In the center of the plate which closes the bottom of each of the short cylindrical tubes is inserted but in a loose and not permanent manner, another cylindrical or other shaped wire and which will call the central wire, standing at right angles to the axis of the aforesaid cutting cylinder, having an enlargement, head or nut on that extremity of it which appears within the cavity and being of such a length that the other extremity terminates in the external surface of the said cutting cylinder. To the external extremity is secured in a permanent manner a circular plate not flat but curved to the periphery of the aforesaid cutting cylinder of a diameter nearly equal to that of the tube in which it is located and having as many perforations made in it as there are cylindrical or other shaped wires as already mentioned made into the plate in the cavity of the tube opposite to it, these perforations being somewhat larger than the wires which pass through them. Between the two plates in the two opposite extremities of each of the short cylindrical tubes above mentioned one made fast to the said tube the other moveable in it, is a spiral or other spring or springs the intention of which is to allow the external and moveable plate, as the dough is pressed into the tube to rise or recede from it, and when the cutting cylinder

cylinder

Mar 13, 1832

6963X

cylinder shall have turned sufficiently to admit of it, to a proper distance, to be removed from the tube already perforated and fit to begin the process. The use of the enlargement, head or not on the internal extremity of the aforesaid central wire is to prevent the internal and movable plate to which it is attached from falling out of its tube, when it is in a declining or pendular position. It need scarcely be added that the external surface of the last mentioned plate may have any name or device engraved or otherwise made upon it that may be desired, and this will be the only mark effected in the making those articles the dough of which does not appear to be perforated, &c. - in this case no wires will be wanting in any of the short cylindrical tubes except the central wire and of course no projection whatever in the movable plate. The short cylindrical tubes in order to turn enable the operator to obtain the greatest number of pieces of biscuit from a given quantity of dough should be arranged in longitudinal series in such manner that the individual tubes of any two contiguous series should not be opposite to, but evenly intermediate between those of each other, the distance apart of these tubes in every direction being the least possible that circumstances will admit. In using the machine as here described and which is complete, the dough is placed upon the slab after the slab itself as well as the remaining machinery have been dusted over with flour to prevent its sticking, the roller nearest to the dough is set in motion by a crank or any other means, this carries the slab with the dough upon it underneath the said roller, and the motion being continued underneath another until it be sufficiently flattened when the motion being still continued the dough is carried under the cutting cylinder, enters the short cylindrical tubes before described and driving the iron plate to &c. by the action of the spiral springs so soon as the cutting cylinder shall have turned so far from the aforesaid slab as to admit of it, when the whole plate of dough shall have passed under the said cutting cylinder and a proper distance beyond it, the iron plate will be passed to the iron, the iron plate so placed among the dough the slab to turn back to its former position.

6903X

Mar. 13, 1832

position and the same process repeated. Perhaps a suitable method of constructing a machine utilizing the same principles will be as follows. Let there be provided a suitable frame of wood or other material in which are to be secured, so that they may be capable of revolving when applied to use four or more cylindrical rollers of the same length as the aforesaid cutting cylinder of convenient, and better probably than otherwise, of one and the same diameter. Let the axis of these be so placed, that the upper surface shall be in one and the same horizontal plane, and let this plane, as near as may be convenient, be coincident with the horizontal plane of the aforesaid frame.

The three or more cylindrical rollers first above mentioned in this one specification together with what we have denominated the cutting cylinder are placed immediately over the said four cylindrical rollers just in the present modification described and at the same distances therefrom as they were directed to be from the rectangular slab aforesaid; and of the four last mentioned cylindrical rollers, to wit, that over which is placed the cutting cylinder aforesaid may have its external curved surface composed of some suitable elastic covering for the purpose ~~for the purpose~~ of enabling the short cylindrical cutting tubes more effectually to perform their duty than they otherwise might.

To obtain the proper proportionate velocities of these various cylinders &c. let appropriate pulleys or wheel work be made use of to connect each of the machinery as required, and let also stationary slabs or planes of wood or other suitable material or small receding rollers be placed between each successive pair of cylindrical rollers to support the dough from falling while it is being conducted to the next pair, and the operation may probably be better done than by the machine first and herein described. At that end of the frame at which the dough is received an inclining inclined table or hopper should be provided and made fast to the said frame, the use of which table or hopper is to introduce the dough to the

6963x

Mar 13, 1832

the first and more distant pair of cylindrical rollers thereby the even
agency of the former with stationary slabs or small revolving rollers
to be conducted to the second and less distant pair of rollers, then again
by the slabs or its substitute, rollers or rollers to be third and still less distant
pair of rollers, and ultimately to the cutting cylinder aforesaid when it
is to be made into the form of biscuit &c. &c.

At the opposite end of the frame aforesaid are inflexible plane, inclined
at a convenient angle to the horizon of a convenient length. & having a width
equal to the length of the cylindrical rollers aforesaid is to be made just in
such a manner as best to avoid touching the cylindrical roller or which
is placed the cutting cylinder. Down this inclined plane it is intended
the biscuit be to together with what may be called the scrap or refuse dough
shall fall or descend and then be received on a feeding cloth having a
width equal to the length of the aforesaid cutting cylinder which feeding
cloth passes horizontally around two cylindrical rollers so as to fit
tight thereon and from which the biscuit to be to be taken and carried
to the oven and the refuse dough to be worked over again and lastly it is
possible that the work we desire over machinery to perform may be
done best of all, by constructing it in such a manner that the dough
shall descend vertically downwards or nearly so till it comes to the
cutting cylinder aforesaid which will deliver it by the help of the
inclined plane aforesaid upon the horizontal feeding cloth just
mentioned. In this latter case, neither the intersecting slabs or slabs
nor roller or rollers will be of any use or if so of very little, all that is
important is by wheels or pulleys to give the proper and appropriate
velocities to the different pieces requiring to be put in motion.

It is to be added that obvious means very similar to those already
handed described are requisite to be resorted to in all the modi-
fications of our principles or rather of our machinery to prevent
the dough from spreading beyond the extremities of the cylindrical
rollers and the cutting cylinder;

Remains now for us to say in what consists that which
we claim as our and original with us in the foregoing article
machinery

Mar 13, 1832

Machinery. We claim as new, the use of two or more cylindrical rollers sufficiently to reduce the dough to its desired thickness in connection with the aforesaid cutting cylinder.

And we claim as new the use of the aforesaid cutting cylinder containing cutters of the ordinary description, whether it be so constituted as to make circular imitations on the same or similar articles of any other shape or form whatever.
